MONTAGUE Tabor PICKSTONE, OF HAMPSTEAD, ENGLAND, ASSIGNOR TO THE PNEUMATIC LOOM SYNDICATE LIMITED, OF BIRMINGHAM, ENGLAND.

PICKING APPARATUS FOR WEAVING-LOOMS.

1,306,190.

Specification of Letters Patent. Patented June 10, 1919.

Application filed August 28, 1917. Serial No. 188,694.

To all whom it may concern:

Be it known that I, MONTAGUE Tabor PICKSTONE, of 64 Alexandra road, Hampstead, county of Middlesex, England, have 5 invented certain new and useful Improvements in Picking Apparatus for Weaving-Looms, of which the following is a specification.

This invention relates to looms for weaving and particularly to that type of loom in 10 which the propulsion of the shuttle is effected pneumatically.

Prior to the date of my invention it has been proposed to use air compressing apparatus in some cases comprising a cylinder and piston, the latter being operated within the cylinder by the aid of gear wheels or suitably shaped cams with the object of providing a sufficient pressure of air to propel 20 the shuttle from one side of the loom to the other and for drawing the shuttle to the extreme outer end of the shuttle box by air suction to enable the shuttle to be held in position within the box by means of a catch 25 device. In other types of apparatus of the pneumatic kind it is difficult owing to the varying weight of the shuttle and weft to insure that after each pick the shuttle shall 30 come to rest at the inner end of the shuttle box or tube; when the shuttle is loaded it will usually reach its proper position, but when the weft is becoming exhausted the shuttle usually fails to reach such position.

The object of the present invention is to 35 overcome this objection by providing improved means for controlling the movements of the shuttle whereby the latter, prior to being picked, is brought to its correct position within the shuttle box and held there by 40 means of suction produced between the shuttle and the inner end of the box; each shuttle on entering a shuttle box is checked by a cushion of air within the said box and is thus brought to rest; a reduction of pressure 45 is then produced to suck the shuttle to its correct position at the inner end of the shuttle box or equivalent; and a sudden increase of pressure is produced behind the shuttle to propel it back across the loom to the opposite 50 box or equivalent.

The accompanying drawing illustrates, partly in section, one construction of pneumatic picking apparatus according to this invention.

55 A is a shuttle box, which is in the form of

a tube open at one end and provided at the other with a tubular connection B leading to the cylinder C' of a pump C. A piston C² is adapted to slide within the cylinder C' and is connected by a link D to a lever D' 60 pivoted at D² and provided with a bowl D³ that runs in a groove E of a cam E', which is driven in any suitable manner. It will be understood that these parts are duplicated on the opposite side of the loom, the cams 65 being set opposite each other, that is to say displaced by 180°. When the parts are in the positions shown in the drawing the shuttle S is up against the buffer A' at the inner end of the tube A, the piston C² in the cylinder C' is moving over its bottom center 70 being operated from the cam E' through the parts E, D³, D', and D, and the reed is just beating up the fell of the cloth.

As the cam E' rotates in the direction indicated by the arrow the arm D' is rocked about its pivot owing to the alterations in the position of the bowl D³ relatively to the cam shaft due to the shape of the cam groove E. When the cam has rotated through 43° 75 from the position shown the bowl lies in the cam groove in the position indicated by the radial line 2; during this movement the shuttle has been propelled from the box; the piston has been moved up to the top of its 80 stroke, moving over the top center; and the reed has been caused to approach the bottom or rearward end of its stroke.

Further movement of the cam shaft through approximately 245° brings the bowl 90 D³ into the position in the groove E indicated by the radial line 3 on the cam: the piston C² has during this movement come downward to the middle of its stroke where it comes to rest.

During approximately the next 30° of movement of the cam shaft, that is to say, while the bowl D³ is brought from position 3 to position 4 in the cam groove there is no movement of the piston; during this period of dwell the shuttle S (having been, in the meantime, propelled from the other side of the loom) reenters the tube A and, meeting a stationary column or cushion of air, gradually comes to rest in a position 100 within the tube A that depends to a great extent upon the quantity of weft in the shuttles; the reed meanwhile is moving toward the fell of the cloth.

Continued movement of the cam shaft 110

brings the bowl D³ into the position in the groove E indicated by the radial line 1, the cam shaft having thus completed its revolution from the first position. During the 5 movement from positions 4 to 1 the piston has been brought rapidly to the bottom of its stroke thus producing a reduction of pressure at the inner end of the tube A with the result that the shuttle is sucked 10 home against the buffer A' and is held against rebound, until the continued movement of the cam shaft brings the parts again to the first position as indicated by full lines.

While the bowl D³ is moving from position 15 2 to position 3 in the cam groove E it will be understood that the corresponding bowl in the cam on the opposite side of the loom passes through positions corresponding to 3, 4, 1 and 2 of the cam shown.

20 What I claim as my invention and desire to protect by Letters Patent is:—

1. An improved pneumatic picking apparatus for looms, comprising a tubular shuttle box, a cylinder communicating therewith, a reciprocable piston working in said cylinder, and actuating means for imparting forward and return movements to said piston, said actuating means including means for temporarily interrupting return movement 25 30 of the piston at a point between its extremes of reciprocation, whereby a stationary air cushion is provided within said box to arrest movement of an incoming shuttle.

2. An improved pneumatic picking appa-

ratus for looms, comprising a tubular shuttle 35 box, a cylinder communicating therewith, a reciprocable piston working in said cylinder, and actuating means for imparting forward and return movements to said piston, said actuating means including means for 40 temporarily interrupting return movement of the piston at a point between its extremes of reciprocation, whereby a stationary air cushion is provided within said box to arrest movement of an incoming shuttle, said actuating means also having means for subsequently continuing the return movement of the piston to suck the shuttle into position to be expelled. 45

3. An improved pneumatic picking apparatus for looms, comprising a tubular shuttle box, a cylinder communicating therewith, a reciprocable piston working in said cylinder, a cam connected with said piston for imparting forward and return movements 50 thereto, said cam having a portion for temporarily interrupting return movement of the piston at a point between its extremes of reciprocation, whereby a stationary air cushion is provided within the box, said 55 cam also having a portion to subsequently withdraw the piston to suck the shuttle into position to be expelled, said cam also having a portion to move the piston in a direction to expel the shuttle. 60 65

In testimony whereof I have affixed my signature.

MONTAGUE TABOR PICKSTONE.
